UNITED STATES PATENT OFFICE.

GEORGES CLOETENS, OF BRUSSELS, BELGIUM, ASSIGNOR OF ONE-THIRD TO GEORGES LALOUX, OF LIEGE, BELGIUM, AND ONE-THIRD TO LOUIS VAN DER HEYDEN A HAUZEUR, OF BRUSSELS, BELGIUM.

STRINGED MUSICAL INSTRUMENT.

1,392,246.

Specification of Letters Patent. Patented Sept. 27, 1921.

Original application filed January 19, 1920, Serial No. 352,345. Divided and this application filed March 7, 1921. Serial No. 450,497.

To all whom it may concern:

Be it known that I, GEORGES CLOETENS, manufacturer of organs at Brussels, Belgium, 37 Rue de Lauzanne, a subject of the 5 King of Belgium, have invented certain new and useful Improvements in Stringed Musical Instruments; and I do hereby declare the following to be a full, clear, and exact description of the invention, such as will enable others skilled in the art to which it 10 pertains to make and use the same, reference being had to the accompanying drawings, and to letters or figures of reference marked therein, which form a part of this specification.

This invention relates to stringed musical instruments in which the strings are struck by hammers, being a division of an application entitled, Stringed musical instruments, 20 filed Jan. 19, 1920, Serial No. 352,345.

The object of the invention is to provide means for modifying the sounds produced by the strings to produce the effects of strings which are plucked, *i. e.*, effects similar to 25 those produced by harpsichords, harps, etc.

The above result is attained according to the present invention by positioning hard pieces of metal, ebonite, or other suitable material, in close proximity to the strings so 30 that the latter in vibrating strike against these pieces with more or less force.

Provision is made for bringing the hard pieces closer to or for moving them farther away from the strings in order to vary the 35 effect produced by the vibrating strings striking against them.

In the accompanying drawings, which show, by way of example, a constructional form of the invention,—

40 Figure 1 is a partly diagrammatic view of the general arrangement of the strings of a piano and of the apparatus constituting the invention.

Fig. 2 is a fragmentary sectional view of 45 Fig. 1 at right angles to the strings; and

Fig. 3 is a section on the line 3—3 of Fig. 2.

The strings 9 are stretched in the usual way over the plate 1, 2. They are operated in 50 the usual way by hammers (not shown) acting at a certain distance from the front part 1 of the plate.

The apparatus constituting the present in-

vention comprises a supporting bar 3 of wood or light metal in one or more sections 55 positioned above the strings, preferably near the hammer line.

Above the strings of each of the notes (each note may be produced by a triple string as illustrated in Fig. 2) the bar 3 is 60 traversed by a rod 4 bent at its lower end to extend transversely above the strings of each note in close proximity thereto. The rods 4 are of metal, ebonite, or other similar hard material, and they are mounted to slide 65 vertically in the bar 3, in order that the position of the bent lower ends with respect to the strings of the several notes may be adjusted, and they are secured in adjusted position by means of screws 5.

Overlying the supporting bar 3 adjacent one end thereof is a wedge member 7 which coacts with an inclined face on the bar. This wedge member is actuated through a rod 8 provided with a handle member near the 75 key-board. Actuation of the wedge by means of the rod 8 causes the bar 3 to be depressed, thereby bringing the hard pieces 4 nearer to the strings. A spring 6 tends to constantly move the bar 3 and hard pieces 4 80 away from the strings.

When the bar 3 is in its highest position, the strings when vibrating do not come into contact with the hard pieces 4 but produce the usual sounds of the piano. When, on the contrary, the bar is depressed the maximum distance provided for by the operation of the wedge 7, the hard pieces 4 are in such close proximity to the strings that substantially the full effect of plucked strings 90 will be obtained. For the intermediate positions of the bar, the effect of plucked strings combined with that of the ordinary piano will be obtained.

It will be understood that the end of the 95 supporting bar 3 opposite that engaged by the wedge 7 will be supported by suitable means permitting the movement of the supporting bar caused by the wedge.

Having now described my invention, what 100 I desire to claim and secure by Letters Patent is:—

1. A stringed musical instrument played by hammers, having hard pieces mounted for movement toward the strings, and means for 105 moving said pieces into position to be struck

by said strings when the latter vibrate without bringing them into actual contact with said strings when the latter are at rest.

2. A stringed musical instrument played by hammers, having a bar positioned transversely above the strings in proximity to the hammer line, adjustable rods carried by said bar bent at their lower ends to form hard pieces extending transversely above the strings of the several notes, and means for

moving said bar toward said strings, to position said hard pieces to be struck by said strings only when the latter vibrate.

In testimony whereof I affix my signature in presence of two witnesses.

GEORGES CLOETENS.
